UNITED STATES PATENT OFFICE.

JOHN WILLIAM WHITE, OF BUFFALO, NEW YORK.

FUEL PUMP.

Application filed November 28, 1924. Serial No. 752,554.

This invention relates to an improvement in fuel pumps, and more particularly in fuel pumps of the type disclosed in my co-pending application, Serial No. 693,929, filed February 19, 1924.

The primary object of this invention is to provide a fuel pump which comprises a chamber in which a bellows and a piston for actuating the same are located, pivoted 10 means for actuating the piston and adjustable spring mechanism for holding the latter normally in the inactive position.

The primary object of this invention is to provide in a pump for liquids, valve mechanism so formed and located that it can be made with a minimum handling of the material.

A further object of this invention is to provide valve mechanism including valves 20 which can be used as either intake or outlet valves by reversing the position of certain parts, the elements in each valve being identical and interchangeable.

Other objects will appear from a consideration of the following description taken in connection with the drawings which form a part thereof, and in which

Fig. 1 is a cross section taken along the line 1—1 of Fig. 4;

30 Fig. 2 is a sectional view taken along the line 2—2 of Fig. 1;

Fig. 3 is a front elevation of the pump; and

35 Fig. 4 is a sectional plan view taken along the line 4—4 of Fig. 1.

Referring to the drawings, the reference numeral 10 is employed to designate a pump casing which comprises a body portion 11 and a head 12 detachably secured by bolts 13 in position to seal the chamber 14 of the body portion.

As in my prior application, this pump is intended to be mounted upon the crank case 15 of a hydro-carbon engine and to be actuated by a cam or roller on the cam shaft (not shown) of such engine.

Mounted to reciprocate within the chamber 14 and below the head 12 is a piston 16 guided in its movement by the contact of the skirt 17 with the walls of the chamber. Depending from a boss 18 on the lower face of the piston 16 is a strap 19 pivotally secured to the boss by a pin 20. The chamber 14 is in direct communication with the interior 55 of a crank case 15 by means of a passage 21, shown particularly in Fig. 1. Pivotally

mounted on a pin 22 in the casing is a lever 23, one arm 24 of which is pivotally secured to the strip 19 by a pin 25. The opposite arm 26 extends into the crank case 15 and is so formed at its outer end to engage with a cam or roller on the cam shaft of the engine in any suitable manner, as for example that shown in my co-pending application.

Projecting from the lever 23 preferably below the pivot pin 22 is an arm 27 having a boss 28 on its outer face. Through the outer wall of the casing 10 is bored a passage 29, into the chamber 14, which is normally closed by a threaded plug 30. The lever 23 is held in the inoperative position shown in Fig. 1 by means of a coil spring 31, one end of which encloses the boss 28 while the other end, entering the passage 29 70 bears against the plug 30. Obviously by shifting the position of the plug 30 the tension of the spring 31 can be adjusted as desired. The passage 29 is preferably made of considerable length so that it will function to position one end of the spring 31, while the other end is positioned by the boss 28.

In the space between the top of the piston 16 and the head 12 is located a bellows 32 85 open at one end, the closed end of the bellows resting against the face of the piston 16. At the open end of the bellows is provided an annular flange 33, which, as shown in Figs. 1 and 2, rests between the top of the body portion 11 and the head 12 and is secured in that position by means of the bolts 13. Suitable gaskets 34 are provided to seal this connection.

It will be noted that when the piston 16 95 is in the position shown in Figs. 1 and 2, the bellows occupies its normal expanded position. When the piston, however, is raised the bellows will be contracted and will thus perform the pumping function set forth below. In the head 12, preferably above the center of the bellows 32 is provided a valve mechanism which comprises an inlet valve 35, a relief valve 36 and an outlet valve 37.

These valves are all shown in section in Figs. 1 and 2 and it will be noted that they are identical in construction and size. The chambers of the three valves are bored into the head and are threaded at 38 to receive 11 annular plugs 39 which are preferably located by means of slots 40 in which the

screw driver or other tool may be inserted. The upper end of each plug 39 is cut away to provide an annular recess 41, while at the inner ends of the valve chambers are formed similar recesses 42 for a purpose to be described later. Extending from the top of the valve chamber is a passage 43 directly above the passage 44 in the plug 39. Annular recesses 45, formed in the inner walls 10 of the passages 43 and 44 provide annular rings 46 either of which can be used as a seat for the valve disc 47. The valve disc 47 is held in its desired position by means of a coil spring 48, one end of which spring 15 bears against the disc 47, while the other end rests in one of the recesses 45, depending upon the seat on which the disc 47 rests. The disc 47 is preferably provided with a boss 49 which projects into the end 20 of the spring 48, and thus functions to hold it in the proper position.

The passage 43 of the outlet valve 37 is extended to the outer face of the head 12 by means of an internally threaded tap 50. 25 (See Fig. 2.) The passages 43 of the intake valve 35 and the relief valve 36 are connected by a transverse channel 51 drilled from the front face of the head 12, as shown in Fig. 1, the outer end of this channel being enlarged at 52 and suitably threaded internally. These valves 35, 36, and 37 are, as shown in Fig. 4, preferably triangularly located in order to condense space and to facilitate manufacturing. 30 In the intake valve 35 the disc 47 normally rests against the upper seat 46 being held in that position by the spring 48, the lower end of which enters the recess 45 of the passage 43. In the relief valve 36 and the outlet 40 valve 37 the disc 47 rests on the lower seats 46, while the upper ends of the springs 48 enter the recesses 45 of the passages 44.

Under normal conditions the reciprocation of the piston 16, by reason of its connection with the cam shaft causes the intake valve 35 and outlet valve 37 to function in the usual manner. When, however, the chamber to which the fuel passing through the outlet valve leads is filled, the fuel in 45 the line will present resistance to the lifting of the disc 47 in the outlet valve. When this resistance increases beyond a predetermined limit, the disc 47 of the relief valve 36 will rise and allow the excess fuel 50 to escape through the passage 43 into the intake channels 51.

In order to regulate the action of the relief valve the plug 39 is advanced further than in the intake or the outlet valve, thus increasing the tension of the spring 48 and preventing the raising of the disc 47 under normal pressure. A heavier spring 48 may be used in the relief valve, but in order to 55 keep the parts interchangeable, this is not advisable, particularly since the same result

can be obtained by advancing the plug 39.

When the piston 16 is raised the bellows 32 is contracted and any fuel or other liquid in the bellows is normally expelled through the outlet valve 37. Upon the lowering of 70 the piston 16 the bellows 32 will return to its normal position, this movement opening the intake valve 35 and drawing fuel therethrough into the bellows, from which on the next reciprocation of the piston 16 the fuel 75 will be expelled. This operation of the bellows, due to the form of the wall which functions like a spring and always tends to return to its normal position is well known and need not be discussed in greater detail. 80

From the above description it will be noted that the arrangement and location of the valve 35, 36 and 37 is such that the chambers can be drilled simultaneously. Since these chambers are of these same dimensions 85 the plugs 39 are interchangeable and the moveable parts of the valve, the discs 47 and spring 48, which are also the same in construction, can be inserted and located without difficulty. 90

While one embodiment of this invention has been shown and described, applicant is not limited thereto, since it is obvious that other embodiments can be made without departing from the spirit and scope of this invention as set forth in the following claims. 95

Having thus set forth my invention what I claim as new and for which I desire protection by Letters Patent is:

1. In a fuel pump mounted upon the 100 crank case of a hydrocarbon engine and comprising a chambered body portion and a head, a bellows in the chamber of said body portion and secured by the means uniting said portion to said head, in a horizontal position so that it contracts and expands in a vertical plane, a lever pivotally mounted on said body portion, one end of said lever extending into said crank case to be actuated by the engine and the other end extending into said chamber, a piston in said chamber pivoted upon and supported by the other end of said lever in contact with said bellows, adjustable spring means normally holding said lever and piston to permit the 110 bellows to expand and valve mechanism in said head comprising intake, outlet and relief valves. 115

2. In a fuel pump mounted upon the 120 crank case of a hydrocarbon engine and comprising a chambered body portion and a head, a bellows in the chamber of said body portion, and secured by the means uniting said portion to said head, in a horizontal position so that it contracts and expands in a vertical plane, a lever pivotally mounted on said body portion, one end of said lever extending into said crank case to be actuated by the engine, and the other end extending into said chamber, a piston 125 130

in said chamber pivoted upon and supported by the other end of said lever in contact with said bellows, an arm on said lever, a plug adjustably mounted in said body portion, a spring in said chamber resting against said arm and said plug acting to hold said piston normally in a position to permit said bellows to expand and valve mechanism in said head comprising intake, 10 outlet and relief valves.

3. Valve mechanism comprising an intake valve, an outlet valve and a relief valve, the valve chambers of each of said valves containing an annular plug, a valve disc and a 15 spring, said plug, disc and spring in each valve being identical and interchangeable with the plug disc and spring of each other valve.

4. A valve comprising a chamber open at

each end, a plug threaded into one end of 20 said chamber and having a passage therethrough, the inner end of said plug having an annular recess in the wall of said passage, the other end of said chamber enclosing the mouth of a passage opposite and forming a 25 continuation of the passage in said plug, the mouth of said passage being surrounded by a recess similar to the first named recess, a valve disc and a spring said disc being adapted to close the inner end of either of 30 said passages and the spring being adapted to seat in the recess of the passage not closed by said disc and to hold said disc in the sealing position.

In testimony whereof I have affixed my 35 signature.

JOHN WILLIAM WHITE.
